UNITED STATES PATENT OFFICE.

ALFREDO GUILLERMO LEIGH, OF SANTIAGO, CHILE.

AEROPLANE.

1,313,828.

Specification of Letters Patent.

Patented Aug. 19, 1919.

Application filed September 17, 1918. Serial No. 254,473.

To all whom it may concern:

Be it known that I, ALFREDO GUILLERMO LEIGH, a citizen of the Republic of Chile, and a resident of Santiago, Chile, have invented a new and Improved Aeroplane, of which the following is a full, clear, and exact description.

This invention relates to aeroplanes or flying machines of the heavier than air type, and has particular reference to certain novel structural features that serve to make the machine self stabilizing and possessed of other features of advantage.

Among the objects of the invention, therefore, is to provide an aeroplane possessing both inherent lateral stability, and inherent longitudinal stability.

Another object of the invention is to provide an aeroplane having special structural features serving to increase the strength and reduce the weight thereof.

Another object of the invention is to reduce the head resistance to the minimum.

Another object of the invention is to construct an aeroplane in which the angle of incidence is variable and regulated by the speed both automatically and at the command of the pilot, enabling him to make the same maneuvers that large birds execute when alighting in a gliding flight.

Another object of the invention is to provide an aeroplane capable of alighting in a very small space, and at low speed.

A still further object is to give the pilot absolute control over the machine so that he is able to maneuver in all ways that are now possible in existing machines, with the added advantage that such operations may be made with greater rapidity, efficacy, and safety.

Another object of the invention is to so arrange the fuselage as to give the pilot greater range of visibility in all directions.

Owing to the qualities of inherent stability possessed by this machine, laterally and longitudinally, I have proved by actual practice in the air that it flies perfectly with any wind, no matter how irregular the wind may be, and with winds whose velocities are in proportion to the load carried by the machine. By unity of surface, it is possible to stop the motor and with simple maneuvers of direction, realize the sailing flight simulating the flight of the condor or albatross. In horizontal flights, no matter how stormy the atmosphere, the pilot will

only be required to control the rudder so as to guide the machine to the right or to the left. Using gravity as a motor and taking advantage of the force of the wind, it is necessary to direct its course only, this aeroplane maintaining itself and traveling with perfect stability the same as a ship on the ocean.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation of my improved construction.

Fig. 2 is a plan view of the same.

Fig. 3 is a left side elevation.

Fig. 4 is a front view in diagram illustrative of the novel principle involved in this construction.

Figs. 5, 6 and 7 are diagrams in side elevation showing the automatic change of position assumed by the machine when dropped substantially nose downward; and

Fig. 8 is a sectional detail indicating the relation of the auxiliary plane of high aspect ratio to the main lifting plane, as well as the longitudinal sectional form of the latter plane.

Referring now more specifically to the drawings 10, 10, are two main lifting wings lying essentially in the same horizontal plane, but spaced from each other over the fuselage 11, the space being bridged by means of two stream line bars 12 and 13. The inner end portion of each wing 10 is curved downward forming a wall 14 which merges into the side wall of the fuselage at about the line 15. Through each of these walls 14 are formed windows 16 and 17 opposite the two seats 18 and 19 respectively for the pilot and passenger.

20 indicates a straight, long and relatively narrow auxiliary lifting plane which I term the plane of high aspect ratio, the same extending entirely across the machine from 21 to 22. This plane 20, therefore, is long enough to reach from tip to tip of the two wings. This plane of high aspect ratio may be essentially flat, although preferably I

form it cambered upward as shown in Fig. 8. The rear or trailing edge 23 of this plane coincides with the vertical plane 24 passing through the front or leading edge 25 of the main or lifting wings 10. The plane 20 is located below the plane of the wings 10 leaving a clear space 26 horizontally between them. Obviously any suitable guys or braces may be employed to hold the parts 10 in operative position, but with such parts I am not particularly concerned except as stated below. This auxiliary plane 20 serves to automatically stabilize the entire machine with respect to the fore and aft directions, 15 and this plane while being carried in rigid and parallel relation to the main plane 10 may obviously be carried at any desired elevation with respect to the plane of said main plane 10 so long as the geometric planes in 20 which the two planes 10 and 20 are located remain substantially parallel.

27 indicates the propeller at the front of the fuselage, and with its axis extending rearward through the center of gravity 28 of 25 the machine. At the rear end of the fuselage are located the tail plane 29, the elevator 30, the fin 31, and the rudder 32 of any suitable construction and controlled by any suitable devices which *per se* are not shown since they 30 are not of my invention.

By reference to the diagrams in Figs. 5, 6, and 7 the line passing through the center of gravity 28 perpendicular to the lifting planes 10 will intersect the plane of the 35 wings at the point 33. The large arrows in these diagrams indicate the direction, parallel to the lifting surfaces, that an ordinary aeroplane is propelled by reason of the motor or what may be called the center of 40 thrust. In this machine the center of thrust passes through the center of gravity. The two points 34 and 35 indicate the two centers of pressure with respect to the lifting and high aspect ratio planes. These points are at 45 the rear and in front of the vertical line of the center of gravity respectively. Considering the machine as a glider purely and set off or dropped from a certain height and with calm air, its trajectory is or may be as 50 shown in Fig. 5 approximately vertical at the beginning, giving to the machine a considerable momentum, but the line of flight will gradually turn toward the horizontal 55 passing through the stage indicated in Fig. 6, and finally alighting with an easy perfect landing at a distance equal to at least four times the height of the fall. The aerodynamic phenomenon that is produced and that gives origin to the longitudinal inherent 60 equilibrium is explained as follows: The speed incident to the rapid fall of the glider causes reactions upward beneath the two planes 10 and 20 at the two centers of pressure 34 and 35, which are initiated at the 65 same time. The center of pressure 34 oper-

ates to support the whole, and the front center of pressure 35 acts as a lever upward and around the center of pressure 34 thereby tending to lift the center of gravity which may be assumed to be suspended from the 70 point 33 until longitudinal equilibrium is established.

Referring now to the diagram in Fig. 4 I have exhibited the special form which gives origin to the lateral inherent equilibrium 75 which is obtained by the combination of three centers of pressure, one central one 34 which for the present consideration may be coincident with the center of pressure of the same number above discussed, and two laterals *a* and *b* acting upon the outwardly and upwardly disposed stabilizing planes 36 and 37 extending from the points of lines 21 and 22 respectively, and held fixed or rigid by any suitable means. These planes are indicated 80 as being arranged in the same inclined planes as lateral struts 38 and 39 leading down to the bottom of the fuselage and in substantially a vertical transverse plane of the center of gravity 28 whereby the upper 85 and outer ends of these struts are located in substantially the transverse line of the point 33 aforesaid. If for instance by reason of a turn or by a gust of wind the aeroplane takes the inclination indicated in dotted 90 lines in Fig. 4 the entire apparatus slips sidewise in the direction of the arrow. Under these circumstances the upward reaction on the wing 36 assumed to be exerted at the center of pressure *a* is superior to the 95 reaction at the center of pressure *b* and tends to cause a moment in a clock-wise direction in said figure around the center of pressure 34 as a lever, and thereby the normal position of lateral equilibrium is soon established.

With reference now to Fig. 8 I wish to point out that the main lifting plane is preferably formed with less fore and aft curvature and in the usual practice the plane 110 ribs 40 between the transverse bars 41 and 42 are slightly upwardly cambered, but back of the bar 42 the planes 10 are substantially flat and terminate at the rear edge 43 in a point that is in line with the bottoms of the 115 bars 41 and 42, and also is in a tangent 44 to the highest point of convexity.

While the high aspect plane 20 is indicated as cambered or upwardly curved at its lower surface it may be otherwise formed. 120 Likewise the lateral stabilizing planes 36 and 37 might be cambered instead of flat as indicated. The one novel feature of construction and advantage that is probably of most importance is involved in the fact that 125 I employ to effect the longitudinal inherent stability, the adaptation in tandem of one or more rigid surfaces of high aspect ratio placed in the front part or below the principal lifting surface in such a way that the 130

distance between the leading or front edge of the principal surface and the rear or trailing edge of the surface of high aspect ratio shall not be longer than the chord of 5 said surface of high aspect ratio. That is to say the plane 20 may be located with its rear edge directly beneath the front edge of the main plane or in the vertical plane 10 perpendicular to the main plane, or it may be positioned forward in its own plane to any distance not to exceed the length of the chord of the plane 20.

I claim:

1. In an aeroplane, a main lifting plane, 15 a plane of high aspect ratio below and ahead of the leading edge of the lifting plane, and means to hold the plane of high aspect ratio rigid with respect to the main plane, and with its rear or trailing edge located at a 20 distance from the leading edge of the main plane not greater than the chord of the plane of high aspect ratio.
2. In an aeroplane, the combination with 25 a main lifting plane, a body and means supporting the body with the center of gravity of the entire structure well below the main plane, of an auxiliary plane of high aspect ratio below and in front of the leading edge of the main plane, and a pair of lateral 30 stabilizing planes rigidly secured opposite the ends of the main and high aspect ratio

planes, the planes being inclined laterally and upward from the ends of the main plane.

3. In an aeroplane, the combination of a 35 plurality of planes providing a main lifting and an auxiliary lifting surface, the main lifting surface being cambered transversely or in a direction perpendicular to the direction of movement and being of low aspect ratio, while the other plane is straight 40 transversely and of high aspect ratio, a body, and means holding the body in position with respect to the two surfaces aforesaid as to bring the center of gravity below 45 and longitudinally between the centers of pressure on the two surfaces whereby inherent longitudinal equilibrium obtains.

4. In an aeroplane, the combination of a main lifting plane, an auxiliary lifting and 50 stabilizing plane of high aspect ratio entirely in front of the main plane but spaced forward therefrom a distance not to exceed the chord of the high aspect ratio plane, means extending between the two planes 55 serving to hold them in rigid position with relation to each other in parallel planes one above the other, a body arranged below the planes aforesaid bringing the center of gravity of the machine below the planes, and 60 means to stabilize the machine laterally.

ALFREDO GUILLERMO LEIGH.
